UNITED STATES PATENT OFFICE.

GEORGE W. BERRY, OF ERIE, PENNSYLVANIA.

SAFETY DEVICE FOR DUMPING VEHICLES.

1,404,684.

Specification of Letters Patent. Patented Jan. 24, 1922.

Application filed February 23, 1921. Serial No. 447,297.

To all whom it may concern:

Be it known that I, GEORGE W. BERRY, a citizen of the United States, residing at Erie, in the county of Erie and State of Pennsylvania, have invented certain new and useful Improvements in a Safety Device for Dumping Vehicles, of which the following is a specification.

The invention relates to a safety device for dumping vehicles, and more especially to automatically actuated safety latching means for hydraulic hoist mechanism described and claimed in my pending applications for U. S. patent filed on the 9th day of June 1919 and on the 3rd day of April 1920, serially numbered 302,880 and 371,045, respectively.

The primary object of my invention is the provision of a device or means of this character, wherein the control valve of the hydraulic hoist mechanism forming the subject matter of the foregoing named applications can be automatically latched and released coincident to actuating the tilting body locking and releasing mechanism constituting the subject matter of an application for U. S. Letters Patent No. 447,298 filed on February 23, 1921, so that damage resulting from premature operation of the hydraulic hoist mechanism is eliminated, as well as any possibility of the premature operation of said mechanism, thereby assuring synchronous cooperation of the hoist mechanism and the latching and releasing mechanism for the successful dumping of the body of the truck, either sidewise or endwise.

Another object of the invention is the provision of a device or means of this character wherein it is necessary to operate the single hand lever for controlling the tilting body locking and releasing mechanism constituting the subject matter of the before mentioned application filed on February 23rd 1921, by me, before the control valve of the hydraulic hoist mechanism can be actuated for the tilting of the dumping body of the truck, so that there is no possibility of this controlling valve being moved when the single hand lever is in neutral position with the tilting body locking mechanism set for locking the body of the truck against side or end tilting action, which would otherwise cause damage or destruction to the said body when the hydraulic hoist mechanism becomes active and also when the single hand lever has been thrown or shifted it is im-

possible to move the same to neutral position when the control valve has been turned for the activity of the hydraulic hoist mechanism and thereby defeating any change in the 60 tilting body locking and releasing mechanism from its previously selected set condition with the result that safety is assured against counteraction between the hydraulic hoist mechanism and the tilting body locking 65 and releasing mechanism for the successful working of the dumping truck.

A further object of the invention is to provide a simple, cheap and effective structure adapted to accomplish the hereinbefore 70 stated objects and having certain details of structure and combination of parts herein-after more fully set forth, while the scope 75 of the application of which will be indicated in the appended claims.

In the accompanying drawings:

Figure 1 is a fragmentary top plan view showing in transverse section the single hand operating lever for the tilting body locking and releasing mechanism and valve 80 stem of the control valve for the hydraulic hoist mechanism, with the latching device or means engaged with the control valve constructed in accordance with the invention.

Fig. 2 is a side elevation of the parts shown in Fig. 1 and in corresponding position, a portion of the base plate being broken away to show in detail the mounting 90 of the latching device or means.

Fig. 3 is a fragmentary sectional view on the line 3—3 of Fig. 2.

Fig. 4 is a detail plan view of one part of the latching device.

Fig. 5 is a perspective view of the other 95 part of the latching device or means.

Fig. 6 is a fragmentary plan view of a motor truck of the tilting body type with the latter removed showing in detail the construction and arrangement of the locking 100 and releasing mechanism in association with the latching device or means illustrated in detail in Figures 1 to 5 inclusive.

Similar reference characters indicate corresponding parts throughout the several 105 views in the drawings.

Referring to the drawings in detail, particularly in Fig. 6 thereof there is shown generally the spaced parallel longitudinal beams or sills A of the motor truck frame 110 or chassis supporting forwardly thereof the driver's or operator's seat B, while super-

imposed and fastened in any suitable manner to the spaced parallel side beams or sills are pairs of spaced parallel transverse bolsters 10, 11 and 12, 13 respectively, which 5 extend laterally beyond the truck frame or chassis on opposite sides thereof, the bolsters or beams 10 and 11 being located adjacent to the seat B, while the bolsters or beams 12 and 13 are located at the rear ends of 10 the frame or chassis and constitute a support for the tilting body or box (not shown). Secured in any suitable manner upon the outer ends of the bolsters or beams 10, 11 and 12, 13 are keeper bearings 14 which 15 constitute pairs of side bearings, while secured in any suitable manner to the outermost bolster or beam 13 of the pair at the end of the truck frame or chassis equally distant removed from the ends of said bolster or 20 beam 13 are keeper bearings 15 constituting the end bearings, which latter with the bearings 14 cooperate with the body or box. Co-acting with the bearings 14 and 15 are the respective pairs of latches or catches 16 and 25 17 which serve to lock the body or box and release the same for end dumping action, the latches or catches being actuated through the medium of connections 18 with a single hand operating lever 19 and which constitutes 30 the subject matter of an application for a U. S. Patent Serial number 447298, filed on the 23rd day of February, 1921 as hereinbefore referred to.

The latching device or means constituting 35 the present invention and illustrated in Figures 1 to 5 inclusive of the drawings, comprises a detent or dog 20 having a collar-like eye 21 adapted to embrace and be splined or keyed upon the shaft 22 carrying the 40 single hand operating lever 19 which is adapted to be manipulated in the rack frame 23 therefor when shifted for controlling the latches or catches 16 and 17 to move the same in selected pairs for the locking and 45 releasing of the body or box of the truck as will be well understood from the subject matter of the application just referred to. The detent or dog 20 is also formed with a fur- 50 cated or forked end 24 for straddling the vertical actuating stem 25 of a control valve 26, the purpose, construction and operation of which is involved in the subject matter of my two pending applications filed on the 9th day of June 1919 and on the 3rd day of 55 April 1920 serially numbered 302,880 and 371,045, respectively.

Surrounding the stem 25 and engaging the plug of the valve 26 is a head 27, the same being made fast to said stem 25 and is cut 60 into on opposite sides in the upper portion thereof to constitute a flat sided boss 28 and lateral rest shoulders 29 on opposite sides thereof. This head 27 is made fast upon the valve stem 25 so that when the valve 26 65 is in closed position the head 27 will have

its boss 28 disposed in alignment with the longitudinal extent of the bifurcation in the forked end 24 of the detent or dog 20 so that the arms or tines of the fork will straddle the boss 28 and rest upon the shoulders 70 29, thereby locking the valve 26 against action, when the single hand operating lever 19 is in neutral position as shown by full lines in Fig. 3 of the drawings. When this lever 19 is shifted in the rack frame 23 from 75 neutral position to the position shown by dotted lines in Fig. 3 of the drawings the dog or detent 20 will be raised to the dotted position shown in said Fig. 3 thereby releasing the valve 26 for actuation, whereby 80 the said valve can be thrown to open position for the activity of the hydraulic hoist mechanism.

On the shifting of the valve 26 the head 27 is correspondingly moved and in the opening of said valve the boss 28 will be disposed crosswise of the forked end 24 of the detent or dog 20 so that the hand operating lever 19 cannot be moved inversely to neutral position during the activity of the hydraulic hoist mechanism, thus it being seen that the latter and the tilting body locking and releasing mechanism cannot be worked counterwise to each other and in this manner perfect safety is assured for the success- 90 ful operation of the dumping vehicle.

From the foregoing it is thought that a clear and comprehensive understanding of the invention will be had and therefore a more extended explanation has been omitted. 100

What is claimed is:

1. In a vehicle, a safety device of the character described, comprising a latching means adapted for coaction with dumping, and locking and releasing mechanisms, and 105 constructed and arranged to be moved with one of said mechanisms to permit one mechanism to become operative and maintain the second mechanism inoperative.

2. In a dumping vehicle, the combination 110 with selective body locking and releasing and dumping mechanisms for the dumping operation, and means coacting with and moved by one of said mechanisms to render one operative and maintain the other mecha- 115 nism inoperative.

3. In a dumping vehicle, a safety device of the character described, comprising a latching means adapted for coacting with body locking and releasing and tilting 120 mechanisms, and operated with one of the mechanisms to move said latching means to render the said mechanisms alternately operable, said latching means including a forked member.

4. Pressure actuating means for tilting vehicle bodies, in combination with a controlling means, locking mechanism at the sides and one end of the body normally retaining the same in a non-tilted position, 130

means controlling said locking mechanism whereby to selectively release certain of the same to allow tilting movement of the body in one direction only, and latching means 5 interconnected with said control means for the locking mechanism and moved therewith for releasing said pressure controlled means from normally inoperative position, only after the actuation of the locking 10 mechanism controlling means to any one of its selective positions.

5. In a dumping vehicle, pressure actuating means for moving the tilting body of said vehicle, a valve included in said pressure means, locking mechanism at the sides 15 and one end of the body normally retaining the same in a non-tilted position, means controlling said locking mechanism whereby to selectively release certain of the same 20 to allow tilting movement of the body in one direction only, a latching means having a forked member adapted to be moved by the controlling means for said locking mechanism for engagement with the valve of the 25 pressure means to hold the same inoperative when the locking mechanism is actuated to selectively release certain of the locking devices.

6. In a dumping vehicle, the combination 30 of means for locking each side and one end of the vehicle box, mechanism for actuating the locking means selectively, means for tilting the box, pressure means for operating

the means for tilting the box, a hand operable valve for regulating the pressure means, 35 a longitudinally movable rod for controlling the locking means, an actuating lever carried by said rod, and a latching member carried by said rod and engageable with the valve for holding the same inoperative when 40 selectively moving the throw lever, said latching means being moved with the throw lever when shifted to selective positions.

7. In a dumping vehicle, the combination 45 of means for locking each side and one end of the vehicle box, mechanism for actuating the locking means selectively, means for tilting the box, pressure means for operating the means for tilting the box, a hand operable valve for regulating the pressure 50 means, a longitudinally movable rod for controlling the locking means, an actuating lever carried by said rod, and a latching member carried by said rod and engageable with the valve for holding the same inoperative when 55 selectively moving the throw lever, said latching means being moved with the throw lever when shifted to selective positions, and means on the valve to hold the latching means when said valve is 60 shifted to operative position and thus hold the throw lever against movement.

In testimony whereof, I affix my signature hereto.

GEORGE W. BERRY.
